United States Patent Office.

JOHN L. ROWE, OF NEW YORK, N. Y.

Letters Patent No. 69,028, dated September 17, 1867; antedated September 7, 1867.

IMPROVEMENT IN TRUSSES.

The Schedule referred to in these Letters Patent and making part of the same.

TO ALL WHOM IT MAY CONCERN:

Be it known that I, JOHN L. ROWE, of the city and State of New York, have invented, made, and applied to use a certain new and useful Improvement in Trusses; and I do hereby declare the following to be a full, clear, and exact description of the said invention, reference being had to the annexed drawing, making part of this specification, wherein—

Figure 1 is a plan of said truss with the padding on one side removed to show the spring.

Figure 2 is a side view of the pad with the supporting-plate in section, and

Figure 3 is a cross-section of the spring at the line *x x*.

Similar marks of reference denote the same parts.

The object of my invention is to give facility for varying the position of the pad in relation to the springs, and to allow the springs themselves to stand in such a direction as to accommodate the body of the wearer, and the pressure and direction of action of the pad are adjusted to suit circumstances.

In the drawing, *a* is a metal spring, of such material or temper that it may be bent slightly as may be necessary to accommodate the shape of the person. At one end of this spring is the back-pad *b*, and a second spring, *c*, laps upon and extends from the other end, and is secured thereto by the folding clamping-plate *d*, the edges of which are folded over to form a slide for the spring *c*, so that it may be drawn in or projected to regulate the pressure, or the entire length of the spring *a c* and a screw may be inserted to hold the springs *a* and *c* and plate *d* together, or said plate may be compressed upon the springs to bind them tightly after they have been adjusted. I make use of two springs, *a* and *c*, one passing on each side of the hips, and *e* is a strap to unite them at the back, contiguous to the pads *b b*. *f* is the covering of leather or other material for the springs *a c*, which covering is removed on one side in fig. 1. The springs *c c* are united together and to the pad-plate *g* by the screw *i*, which allows the springs *c c* to be placed at any angle to each other, or the pad and plate at any angle to the springs, and then tightly secured together. By this arrangement the position and set of the pad can be varied, and the springs *a c* extend around the person at whatever position may be desired for the ease and comfort of the wearer. The pad *h* is hinged at *l* to the pad-plate *g*, and *m* is a screw by which the bottom of the pad can be thrown in, so as to apply the pressure to the proper portion of the rupture.

What I claim, and desire to secure by Letters Patent, is—

The springs *c*, connected with and extending from the springs *a* in the manner specified, in combination with the pad-plate *g*, to which they are united by one bolt, in the manner and for the purposes set forth.

JOHN L. ROWE.
